UNITED STATES PATENT OFFICE.

SAMUEL COHN, OF NEW YORK, N. Y.

DESIGN FOR A LABEL-BLANK.

40,434.

Specification for Design.

Patented Jan. 11, 1910.

Application filed November 13, 1909. Serial No. 527,958. Term of patent 7 years.

To all whom it may concern:

Be it known that I, SAMUEL COHN, a citizen of the United States, residing at the city of New York, borough of Manhattan, in the county and State of New York, have invented a new, original, and ornamental Design for a Label-Blank, of which the following is a specification, reference being had to the accompanying drawing, forming part thereof, in which is shown a face view of a label-blank incorporating my said design.

In said drawing, the label blank is shown as of rectangular form having a shield or plate of irregular outline imposed thereon. The surface of said shield or plate is ornamented to produce a mottled or marbleized effect contrasting with the marginal portions of the label blank. A triangular ornament having a beaded border, is shown in the upper central portion of said irregular shield or plate with its apex lowermost. Upon said triangular ornament is disposed an ornamental device, formed by sprays of foliage, having its upper portion extending

above the top of said triangular ornament, and its lower portion comprising two elliptical members disposed horizontally at either side of said triangular ornament, adjacent to its lower end. A shield with the representation of an eagle issuant bearing a spear is shown superimposed upon said ornamental device, and a crown is arranged above said ornamental device. At both sides of said triangular ornament are disposed conventionalized sprays of foliage which are arranged adjacent to the inclined sides of said triangular ornament. In the lower portion of said irregular shield or plate is arranged a horizontal panel inclosed by sprays of conventionalized foliage forming a border therefor.

I claim—

The ornamental design for a label blank, as herein shown and described.

SAMUEL COHN.
